Attorney

UNITED STATES PATENT OFFICE.

CHARLES WESSOLECK, OF HARTFORD, CONNECTICUT.

SASH-HOLDER.

1,318,468.

Specification of Letters Patent. Patented Oct. 14, 1919.

Application filed June 14, 1919. Serial No. 304,138.

To all whom it may concern:

Be it known that I, CHARLES WESSOLECK, a citizen of the United States, residing at Hartford, in the county of Hartford and 5 State of Connecticut, have invented certain new and useful Improvements in Sash-Holders, of which the following is a specification.

This invention relates to what I shall term 10 a "sash holder". I employ this designation somewhat for convenience and for the further fact that the device has been found of particular utility when used in conjunction with two coöperating sashes. Obviously it 15 may be employed with various kinds of sashes and conceivably in other ways, for instance with doors or other closures. I have several objects in view. Among them are the provision of a device of the character set forth which is capable of inexpensive construction, strong and serviceable, 20 can be easily applied, is efficient in action, and which will hold two sashes or their equivalents in one or more relatively adjusted positions.

In the drawings accompanying and forming part of the present specification, I have shown one of the several convenient forms of embodiment of the invention which to 30 enable those skilled in the art to practice the invention will be set forth in detail in the following description. The novelty of the invention will be included in the claim succeeding said description. I am not necessarily restricted to said disclosure; I may 35 in fact depart therefrom in several respects within the scope of the invention defined by said claim.

Referring to said drawings.

40 Figure 1 is a front elevation of a window equipped with a sash-holder involving the invention.

Fig. 2 is a vertical section on the line 2—2 of Fig. 1 looking in the direction of the 45 arrows.

Fig. 3 is a horizontal section on the line 3—3 of Fig. 2 looking in the direction of the arrows.

Fig. 4 is a vertical sectional elevation the 50 section extending through the keeper.

Fig. 5 is a cross section on the line 5—5 of Fig. 2 looking in the direction of the arrows.

Like characters refer to like parts throughout the several views which are on different 55 scales.

The device comprises in its organization, two elements one of which may be considered as a keeper member and the other a bolt member. Within limits these parts may 60 vary somewhat as to structure although those shown and denoted respectively in a general way by 2 and 3 have desirably met my conditions. There are different ways in which these members 2 and 3 may be employed. 65 Generally the keeper member 2 is united with an upper sash as 4 and the bolt member is associated with a lower sash 5. The bolt member coöperates with the keeper member to hold the sashes fully 70 closed or it may be manipulated in such a way as to relatively operate the sashes so that they may be opened to different positions, as I will hereinafter explain, and then fastened and firmly held. The bolt member 75 is usually accessible only from the interior of a room furnished with these sashes, the result being that when the holder is in active relation and functioning to secure the sashes to each other, they cannot be released 80 exteriorly of the room, the best that can be accomplished being to move both sashes together. In this case access cannot be obtained to the room outside the same by the opening of the sashes yet ample ventilation 85 is provided by way of the opening or openings afforded by the positions of the sashes when secured open.

The keeper member 2 is fastened in some suitable way to one of the stiles of the upper sash and I will set forth the means shown by which I may accomplish this result. Said keeper member may be made in any convenient manner. I prefer that it be of all sheet metal securing in this way 90 strength and rigidity, and as an item comparatively small expense in its production. This keeper member comprises a somewhat elongated tubular body 6 secured by shaping up a proper blank, the back edges of 100 the blank being in abutment practically throughout the length of the body 6. Said body 6 on the rear side thereof has mating cheeks which produce a series of spaced lugs or ears 7, three of them being shown 105 although this number may not always be necessary. The cheeks or sides of these lugs abut solidly and substantially so that in effect they are integral. Said lugs or ears are curved to fit against the bead 8 of the stile 110 which carries the keeper member and they are secured to said stile in some proper

manner as by screws 9. The front side or wall of the tubular body faces the front of the window and it has in it several perforations or holes as 10 of which there may be 5 any suitable number, the holes generally being spaced apart uniform distances.

The bolt member 3, that is the part considered in its entirety, comprises a base 11 having on its upper side the channeled portion 12 in which is disposed the bolt 13 the ends of the bolt being slidable in the channeled portion and through holes in the walls 14 closing the ends of the channeled portion. Fitted around the bolt 13 is a coiled 15 push spring 15 the rear end of which fits against the rear or outer wall and the front end of which acts against the lower end of a thumb-screw (hereinafter described) and normally tends to advance the bolt. Extending 20 through the longitudinal slot 16' of the channeled portion 12 is a thumb-screw as 17 which has a threaded connection with and projects through the bolt about the middle thereof. This thumb-screw as to one of 25 its functions is to facilitate the manipulation of the bolt. The base 11 has several perforations to receive screws 18 or similar fastenings by which the same may be fastened to the upper cross bar of the lower 30 sash in adjacency to the keeper member 2. I might state at this point that the thumb screw 17 may be turned to impinge the bolt 13 against the channeled portion 12 thus either to hold the bolt in its advanced or 35 retracted positions.

The bolt member 3 will be positioned adjacent to the keeper member 2 these parts as I have stated being attached in the present instance, to the lower and upper sashes

5 and 4 with the bolt member in proximity 40 to the keeper member when the sashes are closed. At the latter time the bolt 13 will be positioned in the lowest hole or perforation 10 to lock or fasten together the two sashes. By drawing back the bolt the sashes 45 are released so that the upper sash can be lowered or the lower sash raised and the bolt then shot by its spring 15 into the second of these perforations to again fasten the sashes together. The bolt can be projected into any one of the holes 10 and different degrees of adjustment obtained. The bolt can be locked either in its advanced or retracted position by the thumb-screw 17. When locked in its advanced position the 50 sashes are securely united and cannot be operated exteriorly of the window to obtain access by such operation exteriorly of the window. When the bolt is locked in its retracted position, the sashes may be freely 55 manipulated.

What I claim is:

A keeper member for a sash holder, comprising a tubular sheet metal part, comprising a flattened front having several holes 60 therethrough, the portions of the tubular sheet metal part being brought into abutment on the rear of the same throughout the length thereof and each portion being furnished with longitudinally spaced lugs 70 which mate and fit against each other respectively to engage the bead of a sash.

In testimony whereof I affix my signature in the presence of two witnesses.

CHARLES WESSOLECK.

Witnesses:

W. W. CONVERSE,
HEATH SUTHERLAND.
